UNITED STATES PATENT OFFICE

155,849

DESIGN FOR A COMBINED TELEVISION CABINET, SPEAKER, SCREEN, AND PROJECTOR

Victor Trad, Deal, N. J.

Application June 19, 1948, Serial No. 147,094

Term of patent 3½ years

(Cl. D26—14)

To all whom it may concern:

Be it known that I, Victor Trad, a citizen of the United States of America, residing at Deal, in the county of Monmouth, State of New Jersey, have invented a new, original, and ornamental Design for a Combined Television Cabinet, Speaker, Screen, and Projector, of which the following is a specification, reference being had to the accompanying drawing, forming part thereof.

In the drawing:

Figure 1 is a view in perspective showing my new design for a combined television cabinet, speaker, screen, and projector.

Figure 2 is a top plan view of the combined television cabinet, speaker, screen, and projector, shown in Figure 1. The opposite side of the device is similar to that shown.

The rear of the television set is plain and the face of the projector is conventional, consisting of a lens mounted in front of the cathode ray tube contained within the projector housing.

I claim:

The ornamental design for a combined television cabinet, speaker, screen, and projector, as shown and described.

VICTOR TRAD.
